UNITED STATES PATENT OFFICE

GARNET W. MCKEE, OF ROCKFORD, ILLINOIS

METER CONNECTION

Application filed October 5, 1928. Serial No. 310,460.

The invention relates generally to devices for use in connecting gas meters to service pipes. More particularly the invention relates to that type of connecting device which consists of a rigid or non-adjustable crossbar having at one end thereof a horizontal socket which is tapped to receive the gas supply pipe, a depending coupling-nipple which is connected at its upper end to the socket and has a coupling-ring at its lower end whereby it may be connected to the supply tube of the gas meter, and a second coupling nipple which is provided at its lower end with a coupling-ring whereby it may be connected to the outlet tube of the meter and has its upper end offset and rotatably mounted with respect to the other end of the crossbar so that the fitter or operator in installing the connecting device can adjust one nipple relatively to the other, to register them accurately with the inlet and outlet tubes of the meter.

In meter connecting devices of this character it has been proposed to connect the offset coupling-nipple for the outlet tube of the gas meter to a hollow member which is rotatably mounted in the end of the crossbar opposite the socket, for the reason that with such an arrangement the aforesaid offset coupling nipple may be connected to the gas delivery pipe or house piping without the use of any form of a union connection, by simply tapping the top part of the hollow rotatable member and threading the end of the gas delivery pipe for connection to the tapped portion. The rotatable member heretofore has been made of a malleable iron or steel casting and has had connected to one end thereof a polygonal shoulder whereby it may be engaged by a wrench or similar tool and turned for the purpose of adjusting the offset coupling nipple relatively to the nipple for the inlet tube. In practice, a construction of this character, although practicable and efficient as far as operation is concerned has proved, nevertheless, to be costly and difficult to produce due to the fact that extreme care must be exercised in machining the end of the bar to form a bearing for the hollow member and the latter must be made

of a machined casting and embody a polygonal shoulder or similar tool engaging surface.

One object of the present invention is to facilitate the manufacture and reduce the cost of meter connecting devices of the type under consideration. This object is attained by providing a construction which permits the rotatable member to be made of a standard extra heavy pipe nipple, avoids the necessity of a polygonal shoulder for turning purposes and permits the crossbar to be machined accurately and economically. In general the improved construction consists in the formation of a fork on the end of the crossbar opposite the socket. The members which form this fork are drilled to form a pair of bearings for supporting a sleeve formed of a standard pipe nipple and are spaced apart a sufficient distance to permit the free use of a standard pipe wrench when it is desired to rotate the sleeve for the purpose of adjusting the subjacent coupling-nipple. With a construction of this character it is manifest that the sleeve is held firmly in bearings which may be machined economically and that the use of a polygonal turning shoulder is obviated.

Another object of the invention is the provision of simple, inexpensive and novel means for holding the sleeve against axial displacement with respect to the fork forming members.

A further object of the invention is to provide a meter connection in which the crossbar is similar in shape to an I-beam so that it has great strength without excessive weight and prevents theft of gas by a crossport drilled longitudinally through the central part of the bar and between the gas inlet socket and the rotatable sleeve.

A still further object of the invention is to provide a meter connection which is of a novel construction and is an improvement upon that disclosed in an application for Letters Patent of the United States filed by me July 5, 1928, Serial No. 290,376.

Other objects of the invention and the various advantages and characteristics of the present construction will be apparent from a

consideration of the following detailed description.

The invention consists in the several novel features hereinafter set forth and more particularly defined by the claims at the conclusion hereof.

In the drawings which accompany and form a part of this specification or disclosure and in which like characters of reference denote corresponding parts throughout the several views:

Figure 1 is a front elevational view of a meter connecting device embodying the preferred form of the invention, parts being shown in section for purposes of illustration;

Figure 2 is a plan view;

Figure 3 is a section taken on the line 3—3 of Figure 1, showing in detail the I-beam construction of the crossbar; and

Figure 4 is a detail sectional view of a meter connection embodying a modified form of the invention.

The invention is exemplified in connection with a gas meter A which may be of any suitable or well known construction and is provided with a vertical inlet tube a at one side thereof and a vertical outlet tube a¹ at the other side. The tubes a and a¹ are generally formed as integral parts of the meter casing and are provided at their terminals with external screw threads a² and a³ respectively.

The improved connecting device which constitutes the subject matter of the present invention comprises a rigid or non-adjustable crossbar B which is preferably formed of cast iron. The central portion of this bar corresponds in cross section to an I-beam or similar structural element and comprises a vertical web b, a top flange b¹ and a bottom flange b². The flanges are formed integrally with the web b and project laterally from both sides thereof. A characteristic and an advantage of utilizing an I-beam formation of this character is that the crossbar is effectively reinforced horizontally as well as vertically although it embodies only a minimum amount of metal. In addition it is practically impossible, due to the comparatively small width of the web, to steal gas by drilling a longitudinal cross port through the bar so as to connect the inlet and outlet tubes of the meter.

A head b³ is formed integrally with one end of the bar B and has formed therein an open ended horizontal socket b⁴. The service pipe a⁴ for supplying gas to the inlet tube a of the meter is connected to the outer end of this socket b⁴ by a screw thread connection b⁵. A vertically extending coupling-nipple C has its upper end connected to the bottom of the socket b⁴ by a screw thread connection b⁶ and is adapted to deliver gas from the service pipe a⁴ to the inlet tube of the meter A. A coupling-ring e engages a flange c¹ on the lower end of the nipple C and is threaded to engage the screw thread

a² on the inlet tube a so as to connect said nipple and tube and form a gas-tight connection therebetween.

The crossbar B is provided at the end opposite the head b³ with a fork b⁷ which consists of a pair of fork-forming members b⁸ and b⁹ positioned one above the other. These members are formed integrally with the flanges b¹ and b² respectively and are connected together by a C-shaped member b¹⁰. The latter is formed integrally with the web b. The member b⁸ has drilled through the central portion thereof a cylindrical hole or aperture b¹¹ which has a vertical axis and is parallel to the nipple C at the other end of the crossbar. This hole b¹¹ is coaxial with a cylindrical hole b¹² which is drilled in the lower fork-forming member b⁹. Said holes b¹¹ and b¹² are equal in diameter and form top and bottom bearings for a vertically extending cylindrical sleeve D. A characteristic of utilizing a fork for supporting said sleeve in lieu of a solid head or tubular portion as exhibited in the aforesaid patent application (Serial No. 290,376) is that the sleeve is more rigidly supported and the machining of the cross-bar may be done more accurately and economically.

The sleeve D is preferably formed of a standard extra heavy pipe nipple the outer periphery of which is ground so that it fits accurately within the holes b¹¹ and b¹² (see Figure 1). The upper end of the sleeve D projects upwardly of the upper fork-forming member b⁸ and is provided with an external screw thread d whereby it may be connected to the outlet pipe E which is connected to deliver gas from the meter to the various points of consumption. The lower end of the sleeve projects downwardly of the lower member b⁹ so that it may be connected as hereinafter described to a coupling nipple F. The sleeve D is rotatable in the fork and is held in the holes or bearings b¹¹ and b¹² against axial displacement by a stud d¹ which is fixed in the outer end of the lower fork-forming member b⁹ and extends into an annular groove d² formed in the outer periphery of the sleeve. This stud and slot connection permits the sleeve to be rotated in the fork and holds the sleeve and crossbar in connected relation. The fork-forming members b⁸ and b⁹ are spaced apart a sufficient distance to permit the central portion of the sleeve D to be gripped or engaged by a standard pipe wrench so that the sleeve may be turned to connect it to the gas outlet pipe E. By having a space of this character between the fork members the sleeve D need embody no polygonal turning shoulder and consequently may be made from a standard pipe nipple.

The coupling nipple F serves to connect the outlet tube a¹ of the meter A to the sleeve D. The upper end of said nipple is pro-

vided with an external screw thread f which is adapted to engage a corresponding internal thread formed in the lower end of the sleeve D. A coupling ring f^1 engages a 5 flange f^2 on the lower end of the nipple F and is internally threaded to receive the screw thread a^2 on the tube a^1 to connect said nipple and tube and forming a gas-tight connection therebetween. Since it is 10 necessary to provide for variation or change in the spacing between the coupling nipples so they may be made to register with the inlet and outlet tubes of the meter, the coupling nipple F is of the offset or swivel type. 15 By means of this construction it is only necessary, when adjustment is desired, to rotate the sleeve D and correspondingly move the nipple F horizontally towards or away from the nipple C at the opposite end of the 20 bar.

In practice, the meter connection, including the bar B, the sleeve D and the nipples C and F together with their coupling rings c and f^1 , is assembled at the factory and 25 shipped to the user as a unitary device. In installing the connection, the crossbar B is rotated so as to effect connection of the gas inlet pipe a^4 to the socket b^4 . The sleeve D is then rotated by inserting a wrench between 30 the fork-forming members b^8 and b^9 . This rotative movement is utilized to connect the upper end of the sleeve and the contiguous end of the gas outlet pipe E. The sleeve D and nipple F are then rotated together until 35 the spacing between the nipples C and F accurately correspond to the spacing between the meter tubes a and a^1 . After this has been done, it is only necessary to secure the tubes in place by means of the coupling rings c 40 and f^1 .

In Figure 4, a modified form of the invention is shown. In this form the upper end of the rotatable sleeve is enlarged to 45 form a shoulder d^3 which abuts against and rests upon the top face of the upper fork-forming member. This enlarged portion is provided with an internal screw-thread d^4 for connection with the gas outlet pipe. The sleeve is held in the fork of the cross bar 50 against axial displacement by a ring d^5 which is welded or otherwise fixedly secured to the central portion of said sleeve and bears against the bottom face of the upper fork-member.

55 The meter connecting device disclosed herein exemplifies an improved connection of the type that consists of a rigid or non-adjustable crossbar having at one end thereof a horizontal socket which is adapted to receive the gas supply pipe. It may be manufactured at a comparatively low cost and permits of accurate and economical machining as well as the use of a standard pipe nipple for the rotatable member. In addition, the 60 device provides for the ready adjustment

of the coupling nipple for the outlet tube of the gas meter and obviates the use of a polygonal turning shoulder. Furthermore, the construction of the crossbar itself lends rigidity to the device and results in the 70 elimination of excess metal and the resultant additional weight.

The invention is not to be understood as restricted to the details set forth, since these may be modified within the scope of the appended claims, without departing from the 75 spirit and scope of the invention.

Having thus described the invention, what I claim as new and desire to secure by Letters Patent, is:

1. In a meter connection, the combination 80 of a rigid bar provided at one end with means for connection to a pipe and a coupling-nipple adapted to communicate with the pipe through said means, a fork at the other end 85 of the bar, consisting of a pair of fork-members disposed one opposite the other and having coaxial holes formed therein, a sleeve fitting accurately and rotatable in the holes and having the ends thereof projecting beyond or outwardly of the fork-members, means at one end of said sleeve for connection to a second pipe, and a coupling-nipple connected to the other end of said sleeve. 90

2. In a meter connection, the combination 95 of a crossbar provided at one end with means for connection to a pipe, the central portion of said crossbar being shaped to form a vertical web and a pair of flanges projecting laterally from said web, a coupling-nipple 100 connected to the crossbar and in communication with the pipe through said means, a pair of fork-forming members at the other end of the crossbar, formed integrally with said flanges respectively, said members being provided with coaxial holes, a sleeve fitting accurately and rotatable in said holes and provided at one end thereof with means for connection to a second pipe, and a coupling-nipple connected to the other end of 105 said sleeve. 110

3. In a meter connection, the combination 115 of a rigid bar provided at one end thereof with means for connection to a pipe and a coupling-nipple adapted to communicate with said pipe through the means, a fork at the other end of the bar, consisting of a pair of fork-members disposed one opposite the other and having coaxial holes formed therein, a sleeve fitting accurately and rotatable in the holes and provided at one end with means for connection to a second pipe, and a coupling nipple connected to the other end of the sleeve and adapted to communicate with said second pipe through the sleeve. 120 125

4. In a meter connection, the combination 130 of a rigid bar provided at one end thereof with means for connection to a pipe and a coupling-nipple adapted to communicate with said pipe through the means, a fork at

the other end of the bar, consisting of a pair of fork-members disposed one opposite the other and having coaxial holes formed therein, a sleeve fitting accurately and rotatable in the holes and provided at one end with means for connection to a second pipe, means associated with one of the fork members for preventing axial displacement of the sleeve relatively to the fork and bar, and a coupling nipple connected to the other end of the sleeve and adapted to communicate with said second pipe through the sleeve.

Signed at Rockford, Illinois, this 29th day of September, 1928.
